[57] CLAIM

The ornamental design for a nip roller for hot seal adhesive packages, as shown and described.

DESCRIPTION

FIG. 1 is a perspective view of a nip roller for hot seal adhesive packages according to this invention;

FIG. 2 is a front view which is identical to the rear view and the top and bottom view; and,

FIG. 3 is a side view where the left and right side of the nip roller for hot seal adhesive packages are identical.

The broken line showing is for illustrative purposes only and forms no part of the claimed design.
